UNITED STATES PATENT OFFICE.

WILLIAM H. MORS, OF WATERFORD, NEW YORK, ASSIGNOR TO THE WATERFORD MANUFACTURING COMPANY, OF SAME PLACE.

SHIRT-BOSOM.

SPECIFICATION forming part of Letters Patent No. 257,967, dated May 16, 1882.

Application filed May 20, 1881. (No model.)

To all whom it may concern:

Be it known that I, WILLIAM H. MORS, of the village of Waterford, county of Saratoga, and State of New York, have invented a new and useful Improvement in Bosom - Shirts, of which the following is a specification.

My invention relates to the art or method of making the bosoms of shirts with reference to the employment of a facing attached to the bosom and shirt at the bottom of the bosom, and therefrom extended downwardly and attached to the shirt-front at a proper distance below the bosom to receive the usual tab for button-hole attachment.

In the accompanying drawing, forming a part of this specification, there is illustrated a shirt-bosom and part of a shirt-front containing my invention, the several parts composing it being designated by letter-reference and described as follows:

The letter A indicates a shirt-bosom, which, at its sides S' S'', is attached to the shirt-front B.

At C there is shown a facing below the bosom-bottom and between the latter and the button-hole tab T.

The letter D designates a line of stitching at the bottom of the bosom by which the latter and the downwardly-extended facing C are attached to each other and to the shirt-front, and at a' the facing at its lower end is attached to the shirt-front and also to the button-hole tab T.

While I have shown the facing stitched to the shirt-front at its sides from S'' to S''' it may, if desired, be made without this attachment, provided it is stitched to the front where joined to the tab T, the latter being detached from m to n.

It will be observed that the facing C is independent and folds or bends independently 40 of the shirt-bosom A, and may be made of inferior and cheaper material.

A shirt-bosom thus made, when worn, keeps its place better than when continued down to the point of button-hole-tab attachment. The 45 cross-seam D serves to keep the bosom flat at the bottom, and tends to force all the wrinkling into the facing below the bosom-bottom and between the latter and the tab.

I am well aware that shirt-bosoms have been 50 patented in which opposite portions of the sides of the bosom were left unattached to the body at a point between where the bosom proper at its top and bottom was attached to the body.

I am also aware that a shirt-bosom has been 55 patented with a bosom-back made in two pieces horizontally joined, and the lower piece being made of a lighter and more flexible material than the upper one, and the bosom stitched to the body with detached edge seams.

Having thus described my invention, what I claim, and desire to secure by Letters Patent, is—

The combination, in a shirt, of the bosom A and independent facing C, the latter below the 65 former and joined to the shirt-front and bosom at the bottom of the latter, and the lower end of the facing attached to the shirt-front with button-hole tab at the bottom of the facing, as shown and described.

Signed at Waterford, New York, this 14th day of May, 1881.

W. H. MORS.
